UNITED STATES PATENT OFFICE.

CHARLES A. KITTS, OF OSWEGO, NEW YORK.

STEAM-BOILER.

SPECIFICATION forming part of Letters Patent No. 677,779, dated July 2, 1901.

Application filed April 3, 1901. Serial No. 54,199. (No model.)

To all whom it may concern:

Be it known that I, CHARLES A. KITTS, of Oswego, in the county of Oswego, in the State of New York, have invented new and useful 5 Improvements in Steam-Boilers, of which the following, taken in connection with the accompanying drawings, is a full, clear, and exact description.

My invention relates to improvements in 10 steam-boilers, and particularly to that class which are used in connection with steam-propelled vehicles.

The object of this invention is to provide an upright-flue boiler with a suitable dry 15 plate or diaphragm loosely mounted transversely within the shell of the boiler for dividing said boiler into lower and upper compartments for the water and steam, respectively, whereby the flue openings or perforations in said dry plate or diaphragm may be 20 readily aligned with similar apertures or flue-openings in the opposite heads of the boiler, so that the flues may be readily inserted through said openings without the necessity 25 of bending said flues to conform to any variation in the alignment of the apertures of the diaphragm with those of the heads.

To this end the invention consists in the 30 combination and arrangement of the parts of a steam-generator, as hereinafter fully described, and pointed out in the claims.

Referring to the drawings, Figure 1 is a 35 transverse vertical sectional view through my improved steam-generator, showing the water-inlet and steam-outlet conduits as connected, respectively, to the lower and upper heads of the boiler-shell. Fig. 2 is a transverse sectional view through the detached diaphragm or dry plate, showing the adjacent ends of the arms which support said diaphragm in position. Fig. 3 is an isometric view of the detached diaphragm or dry plate, showing the relative position of the supporting 40 legs or arms secured thereto.

Similar reference characters indicate corresponding parts in all the views.

As shown in the drawings, this invention consists of a boiler-shell 1, composed of upper and lower sections 2 and 2', having their 45 adjacent ends open and provided with annular flanges engaged with each other and secured together by suitable fastening means, as rivets or bolts *a*. These sections are preferably formed of substantially the same size,

the meeting edges of their open ends being 55 substantially midway between the opposite lower and upper heads 3 and 3', although it is apparent that said sections of the boiler-shell may be of unequal size, if desired, and their meeting edges in closer proximity to 60 one or the other of the heads 3 or 3', this element not being an essential feature of my invention.

The heads 3 and 3' are each provided with a series of flue openings or apertures 4, which 65 are aligned with each other and are arranged to receive the opposite ends of a series of upright flues 5, which ends after being inserted into the heads are then expanded or upset for securing the same in position. The upper 70 head is provided with a steam-outlet passage or conduit 6, and the lower head with a suitable water-inlet conduit 6', which, however, may be otherwise arranged than as indicated in the drawings. 75

Arranged within the boiler or shell 1 is a diaphragm or dry plate 7, which is loosely supported in a plane substantially parallel with the heads 3 and 3', being of substantially the same diameter and general contour 80 as the inner diameter of the shell 1 and is preferably arranged in closer proximity to the upper head 3 than to the lower head 3' for dividing the interior of the shell 1 into a lower water-containing compartment and an 85 upper steam-compartment. The primary object of this plate 7 is to prevent the foaming or undue splashing of the water within the boiler-shell, and although it may be supported in any desired manner, so as to permit its 90 free rotary movement within the boiler-shell and independently thereof, I preferably provide the dry plate or diaphragm with one or more arms 8 and 9, projecting, respectively, from its upper and lower faces, the lower end 95 faces of the depending arms 9 being arranged to rest upon the upper face of the lower head 3' for supporting the diaphragm, and the upper ends of the arms 8 being arranged to engage the lower face of the upper head 3 for 100 additionally supporting the diaphragm in position during the insertion of the tubes 5, it being understood that said diaphragm is provided with a series of apertures 10, corresponding to the number of apertures in one 105 of the heads 3 or 3' or, in other words, corresponding to the number of flues employed in the boiler.

It is well known that in boilers of this character in which the diaphragm is secured firmly in position it is very difficult to aline the apertures of said diaphragm with the flue-openings in the heads, and that therefore when the flues are inserted in position it is necessary to bend the flues in order to conform to the variations in the alinement of the apertures in the diaphragm with those of the heads. By loosely mounting the diaphragm within the boiler, as shown, described, and claimed as my invention, it is evident that when the flues are inserted the diaphragm may be readily rotated a slight distance, thereby alining the apertures of the dry plate with the similar apertures of the heads and permitting the flues to be not only readily inserted, but also obviates the necessity for bending said flues, and thereby destroying their utility and effectiveness. This is a particularly important feature of my invention, and while reducing the expense in assembling the parts of the boiler it also increases the strength of the boiler and permits the diaphragm to readily adjust itself for the purpose of alining the apertures therein with the apertures of the head. Although this diaphragm is formed of substantially the same diameter as the inner diameter of the drum, yet it is apparent that the flue-openings may be made a little larger than the flues, and the diameter of said diaphragm may be slightly less than the interior diameter of the shell for permitting the passage of the steam from the water-chamber to the steam-compartment; but in order to further provide for this passage of the steam the diaphragm is formed with a series of small steam-passages 11, as shown particularly in Fig. 3.

The operation of my invention will now be readily understood upon reference to the foregoing description and the accompanying drawings, and it will be noted that the diaphragm may be otherwise supported than as seen in the drawings—as, for instance, the periphery of said diaphragm may be interposed between flanges projecting from the inner face of the shell in such manner as to permit the diaphragm to rotate, or, rather, adjust itself so as to aline its apertures with the similar apertures of the heads.

Having thus fully described my invention, what I claim as new, and desire to secure by Letters Patent, is—

1. A steam-boiler comprising a shell having opposite perforated heads and fire-flues within the shell and having their opposite ends inserted in the apertures of the heads, and a transverse plate between the heads and provided with perforations receiving the flues, said plate being slightly rotatable for permitting the alinement of its apertures with those of the boiler-heads when the flues are being inserted in position, and means for preventing endwise movement of the plate.

2. The combination with a steam-boiler composed of opposite hollow sections formed

of substantially the same size and having adjacent ends open and secured to each other and their outer ends provided with perforated heads, an intermediate transverse perforated plate between and substantially parallel with the heads, said plate being movable independently of the heads for alining its apertures with those of the heads after the boiler-sections are secured together, and flues inserted through the apertures of the heads and plate and having their opposite ends secured to the heads.

3. A steam-boiler comprising a cylindrical shell having opposite perforated heads, a circular plate loosely supported transversely within the shell and formed of substantially the same diameter as the interior of the shell, said plate being formed with apertures corresponding to the perforations in the heads and provided with steam-passages therethrough, and flues passed through the apertures and perforations of said plate and heads and having their ends secured to the heads.

4. In a steam-boiler the combination of oppositely-arranged hollow sections having their adjacent ends open and secured to each other and their opposite ends provided with heads having flue-openings, a plate loosely supported within the shell between the meeting ends of the sections and one of said heads and arranged substantially parallel with the heads, said plate being provided with flue-openings and steam-passages therethrough, and flues inserted through said openings of the heads and plate and secured to the heads, and means for preventing endwise movement of the plate.

5. In a steam-boiler the combination of oppositely-arranged hollow sections having their adjacent ends open and secured to each other and their opposite ends provided with heads having flue-openings, a plate loosely supported in the shell between the meeting ends of the sections and one of said heads and arranged substantially parallel with the heads, said plate being provided with flue-openings and steam-passages therethrough, and flues inserted through said openings of the heads and plate and secured to the heads and bars or rods secured to the plate and projecting in opposite directions therefrom for engaging the opposite heads and preventing endwise movement of the plate.

6. The combination with an upright tubular boiler of a transverse plate loosely mounted in the boiler between its opposite heads and parallel therewith, said plate being provided with openings receiving the flues and with oppositely-projecting arms engaged with the heads for holding the plate from endwise movement.

In witness whereof I have hereunto set my hand.

CHARLES A. KITTS.
